United States Patent Office.

JOHN BAILLIE, OF SALEM, OHIO.

Letters Patent No. 74,277, dated February 11, 1868.

IMPROVEMENT IN SAW-MILLS.

The Schedule referred to in these Letters Patent and making part of the same.

TO ALL WHOM IT MAY CONCERN:

Be it known that I, JOHN BAILLIE, of Salem, in the county of Columbiana, and State of Ohio, have invented certain new and useful Improvements in a Planing and Resawing-Machine; and I do hereby declare that the following is a full and complete description of the construction and operation of the same, reference being had to the accompanying drawings making a part of this specification, in which—

Figure 1, plate 1, is a side view of the machine.

Figure 2, a view of the top.

Figure 3, a view of the opposite side of fig. 1.

Figure 4, plate 2, a rear end view.

Figure 5, a view of the front end.

Figures 6 and 7, detached sections.

Like letters of reference refer to like parts in the several views.

In fig. 1, plate 1, A is a frame or table, on and in which is arranged the following machinery: In the standard, B, fixed to the top of the frame, is mounted a frame walking-beam, C, at one end of which is hung a bifurcated pitman, D, a detached view of which is shown in fig. 6, plate 2. The lower end of this pitman is connected to an adjustable balance-crank, E, fig. 3, keyed to the end of the shaft F, fig. 5, on which is a balance-wheel, G, and pulley, H, and by which the machine is driven. On the opposite end of the walking-beam is hung a frame, I, fig. 4, plate 2. The lower end of this frame is connected to a vibrating arm, J, fig. 3, plate 1. Said arm proceeds from a rock-shaft, K, journaled in the stay L, fig. 2. Within this frame I, is hung a saw, M, immediately in front of which is a pair of guide-rollers, N, supported in the adjustable stays O. In front of the machine is a pair of feed-rollers, P P', fig. 5, P being secured in the adjustable stay Q, which, by means of the screw R, can be made to approach to or recede from the stationary roller P'. To the lower end of the shaft to which the roller P' is connected, are keyed a crown-wheel, S, and also a pinion, T. In this pinion is engaged a pinion, U, which operates the roller P' by means of the link V, said link being connected to the roller and pinion by adjustable or universal joints W. Motion is given to the crown-wheel S by the bevel-wheel z, on the shaft Y, and which wheel is made to engage and disengage with the crown-wheel by a clutch, z, operated by the handle or lever A'. Arranged in the same way as the feed-roller P, and operated by an adjusting-screw and spring, B', in the same manner, is a smooth guide-roller, indicated by the dotted lines a, fig. 2, plate 1. This roller is placed in front of the pitman, and behind the pitman is a pair of smooth guide-rollers, C', of a similar character, and which are supported in the stays D', figs. 1 and 3. E' is a revolving head of cutters, arranged immediately back of the guide-rollers C', and is driven by the shaft and pulley F', fig. 5, mounted in the stay G', and which receives motion from the pulley H', by means of the belt I', said pulley in turn being driven by the drum J' on the main shaft F.

The planing-apparatus of this machine consists of a pair of chisel-shaped cutters, K, fig. 6, plate 2. A detached view of one is shown in fig. 7. As will be observed, these cutters are fixed between the branches of the pitman, in adjusting-clamps b, so that they can be made to approach or recede from each other, as the thickness of the board to be planed may determine, and which is done as follows: A board, of the proper thickness for two pieces of siding, is intruded edgewise between the feed-rollers P P', and by means of the adjustable roller and spring e, is held close pressed against the plate L'. As the board passes between the cutters K, it is planed on both sides by the downward stroke of the pitman, and also on the edges by the cutter-head E'. A corresponding head of cutters is arranged below the head E', so as to plane the lower edge of the board as it passes through. The board thus planed is ripped through by the saw M, making two pieces of siding. The board, as it is being sawn, is held in position by the guide-rollers N, and restrained from any vertical movement by the check M'. It will be observed that the saw is not hung vertically, but is slightly inclined to one side, so that the pieces of siding, when sawn, will be thicker on one edge than the other, for the convenience of lapping. The elliptical character of the stroke given to the plane-irons is such that the cutting is done in a drawing or shearing-like manner, so that the grain of the wood, however coarse and free it may be, will not splinter and tear, but is cut smoothly, leaving no ridges or markings of the plane. It also cuts with greater ease, and can be run at a very much lower speed, and hence with an increased power, than the ordinary rotary planes,

at the same time it will cut as fast, for the reason that the machine can be fed faster, thereby taking off wider shavings. It will be observed that the saw is hung between two radii of a circle, viz, that described by the walking-beam, and to which the upper end of the saw is attached and operated, and that described by the radial arm J, to which the lower end of the same is connected. Now, as the saw is made to reciprocate, the lower end in the downward stroke will be drawn from a vertical line toward the centre of the vibration of the arm, and thus be drawn back from the timber; at the same time the upper end of the saw will be drawn from a vertical line toward the centre of the vibration of the beam, and hence against the timber. By these two peculiar movements all the teeth of the saw are not engaged at once in the timber, a rake being given it, so that it will run clearly and freely through the stuff. By this arrangement of the radial arm J, guides and frame for the control of the lower end of the saw are dispensed with; hence it will run much easier and lighter than saws encumbered by a frame, as in the ordinary way.

The counterbalance N' , on the crank, is so attached that it can be moved toward the centre or from it, as the length of the crank and other circumstances may make it expedient.

What I claim as my improvement, and desire to secure by Letters Patent, is—

1. The plane-irons K, bifurcated pitman D, as arranged, in combination with the beam C, in the manner and for the purpose substantially as set forth.
2. The saw M, as arranged in combination with the beam C, and radial-arm J, in the manner and for the purpose set forth.
3. The arrangement and combination of the adjustable feed-roller P, link V, pinions J T, and stationary roller P', constructed and operating in the manner substantially as set forth.

JOHN BAILLIE.
